(57) **CLAIM**

The ornamental design for a tubular applicator, as shown and described.

DESCRIPTION

FIG. 1 is a first perspective view of the tubular applicator; FIG. 2 is a second perspective view of the embodiment of FIG. 1;

FIG. 3 is a third perspective view of the embodiment of FIG. 1;

FIG. 4 is a left elevation view of the embodiment of FIG. 1; FIG. 5 is a right elevation view of the embodiment of FIG. 1;

FIG. 6 is a front elevation view of the embodiment of FIG. 1;

FIG. 7 is a rear elevation view of the embodiment of FIG. 1;

FIG. 8 is a top plan view of the embodiment of FIG. 1; and, FIG. 9 is a bottom plan view of the embodiment of FIG. 1.

Elements shown in broken lines are for illustrative purposes only and form no part of the claimed design.

1 Claim, 8 Drawing Sheets
